UNITED STATES PATENT OFFICE.

MYER E. ISEMAN AND JOHN K. HOUGHAM, OF VISALIA, CALIFORNIA, ASSIGNEES OF
ONE-THIRD TO MARC HAROLD ISEMAN, OF VISALIA, CALIFORNIA.

DISPLAY RACK.

Application filed February 23, 1924. Serial No. 694,590.

To all whom it may concern:

Be it known that we, MYER E. ISEMAN and JOHN K. HOUGHAM, citizens of the United States, residing at Visalia, in the county of 5 Tulare and State of California, have invented certain new and useful Improvements in Display Racks, of which the following is a specification.

Our invention relates to that class of display racks which comprise a compact and easily movable structure provided with shelves arranged to support and display the goods in convenient and attractive manner.

The object of our invention is to provide a light, strong and rigid rack, with shelves particularly adapted for different goods and for various and attractive aggregations thereof, of different shapes and piles, or in suitable containers according to the nature 20 of the goods, the shelves being arranged to display the merchandise to the best advantage and to render it easily accessible, the whole device being neat and sanitary.

To this end our invention consists in the novel display rack which we shall herein-after fully describe by reference to the accompanying drawings in which—

Fig. 1 is a perspective view of our display rack.

Fig. 2 is a perspective view of one of the shelves.

Fig. 3 is a vertical cross section, enlarged, and broken, of the rack.

Fig. 4 is a detail section of the frame-wall 35 showing its strap border.

1 is the frame-wall of the rack, which in practice is best made of light matched boards, bound with metallic straps 2, giving by their overlap an appearance of solidity, 40 in addition to border protection. These projecting straps also serve as one of the several fastening points for the skeleton shelf frames. In the present case we have shown merely for illustration six of these shelf-frames, three being on one side of the wall 1 and three on the other, though it will be understood that according to the size of the rack, the shelf frames may be in greater or less number, and may be on both sides of the 45 wall or on only one side according to the location of or space available for the rack.

These skeleton frames are alike in structure, and each is formed of metallic angled straps with their angles facing upwardly, so 50 that one wing of the angle forms a horizon-

tal shelf-supporting ledge, while the other wing forms an uprising confining stop.

The lowermost skeleton frames, one on each side of the wall 1, are designated by the numeral 3, and these together form the stable base or foot of the rack, and carry the casters 4, by which the rack is given ready portability. In practice these foot frames 3 are wider than the overlying skeleton frames, the latter being designated by 5, the object of this being to enable the goods displayed upon the foot frames to be brought forward into better view. Each skeleton frame is well strengthened by an underlying cross brace 6, and by diagonal end braces 7, 70 and each is rigidly secured to the frame wall 1 and its border strap 2.

Associated with each skeleton frame is a shelf 8, though for convenience and to avoid unnecessary multiplication of illustration we 75 have herein omitted some of the shelves. The lowermost shelves are wide to fit a foot frame 3 and the others narrow to be received by the upper frames 5.

These shelves removably rest within the 80 angled frames, and are adapted for reversal therein, that is, bottom for top and top for bottom, according to the nature of the objects to be placed upon them. One face of the shelf is perfectly smooth. The other 85 face has secured upon it at each end a cleat 9, and it also has intervening stiffening cross cleats 10, which are pivoted to the shelf at 11, to enable them to swing to an angle for a purpose to be presently mentioned. These cleats 9 and 10, when the shelf is turned to present them downwardly, lie upon the supporting wings of the angled skeleton frame, and they are thick 90 enough to raise the shelf so that its smooth 95 opposite face, now the top face, lies flush with top edges of the upright angle, or stop wing, while the edges of the shelf lie snugly within said stop wings. Upon the smooth face of the shelves, in this position, goods 100 may be displayed, of such nature and in such aggregations and forms and shapes of piles or pyramids as may be adapted for such a supporting surface. But for other goods and other desired heaps, or for containers for such goods, the shelf is reversed, 105 so that its cleats 9 and 10 are now uppermost, while the shelf itself lies well down within the angled border of its skeleton frame. In this position the several cleats 110

lend themselves as divisional markers to define possible separate piles of objects displayed; and if containers such as are indicated by 12 are used to hold and protect the goods, under glass or screen covers, said containers may be set at an inclination, their forward base edges resting against the stop wings of the skeleton frame and their rear base edges resting against the wall 1. The reason for pivoting the intervening cross cleats 10 will now be seen. Since they must be long enough to rest their ends upon the skeleton frames, when the shelf is turned down, said ends would be in the way of the containers when the shelf is turned up, unless the containers were made small enough to fit in between them. But this arrangement would not look well, as the containers would be separated by unsightly spaces, nor would the full capacity of the shelf be utilized. But by pivoting said cross cleats 10 they may be swung to an angle as shown in Figs. 1 and 2 to remove their forward ends from the vicinity of the skeleton frame stop border and thus present no obstruction to the forward base edges of the containers resting squarely and fully against the stop wing of said frame, and, moreover, the containers may thus fit closely together and fill the full length of the shelf.

As before stated the lowermost or foot shelves are relatively wide. This will enable containers such as are indicated by 13 to be brought more to the front, and to be in plain sight with minimum interference from overlying displays. Accordingly, in order to support the rear base edge of such a forwardly positioned container, thus removed from possible support by the wall 1, we provide temporary supports for said rear base edge. These supports consist of angled ledges 14, Fig. 3, having stems 15

which are removably fitted in sockets 16, in the shelf. The entire display rack is attractively surfaced say, for example, by a coating of white enamel, and the several containers are likewise treated. The device is light and yet strong and may be easily moved from place to place.

We claim:

1. A display rack comprising a frame wall; a skeleton frame with upwardly facing angled border, secured to and projecting from said frame wall; and a shelf adapted to be removably supported within the angled border of said skeleton frame, said shelf having one face smooth and its opposite face provided with cross cleats adapted to rest upon said angled border, said cleats being at each end of the shelf and between said ends, the cleats between the ends being pivoted to the shelf adapting them to be turned to an angle to the shelf width.

2. A display rack comprising a frame wall; a plurality of skeleton frames with upwardly facing angled borders secured to and projecting from said frame wall in vertically spaced relation, the lowermost skeleton frame forming the rack base; and a shelf adapted to be removably supported within the angled border of each of said skeleton frames, each of said shelves having one face smooth and its opposite face provided with cross cleats adapted to rest upon said angled border, said cleats being at each end of the shelf and between said ends, the cleats between the ends being pivoted to the shelf adapting them to be turned to an angle to the shelf width.

In testimony whereof we have signed our names to this specification.

MYER E. ISEMAN.
JOHN K. HOUGHAM.
